(57) **CLAIM**

We claim the ornamental design for a carabiner charging cable, as shown and described.

DESCRIPTION

FIG. 1 is a perspective view of a carabiner charging cable, showing our new design;
FIG. 2 is a front elevational view thereof;
FIG. 3 is a rear elevational view thereof;
FIG. 4 is a left-side elevational view thereof;
FIG. 5 is a right-side elevational view thereof;
FIG. 6 is a bottom plan view thereof;
FIG. 7 is a top plan view thereof;
FIG. 8 is an exploded perspective view thereof;
FIG. 9 is an exploded front elevational view thereof;
FIG. 10 is an exploded rear elevational view thereof;
FIG. 11 is an exploded left-side elevational view thereof;
FIG. 12 is an exploded right-side elevational view thereof;
FIG. 13 is an exploded bottom plan view thereof;
FIG. 14 is an exploded top plan view thereof; and,
FIG. 15 is a left-side elevational view thereof, illustrated with a connector cable in a flexed configuration.
